DESIGN FOR A HOLDER FOR CANS

Orley R. Frost, Port Huron, Mich.

Application July 22, 1940, Serial No. 93,838

Term of patent 3½ years

To all whom it may concern:

Be it known that I, Orley R. Frost, a citizen of the United States, residing at Port Huron, in the county of St. Clair and State of Michigan, have invented a new, original, and ornamental Design for a Holder for Cans, of which the following is a specification, reference being had to the accompanying drawing, forming part thereof.

Fig. 2 is a side elevational view thereof;
Fig. 3 is an end elevational view of the same;
Fig. 4 is a bottom plan view of Fig. 1, and
Fig. 5 is a perspective view thereof.

I claim:

The ornamental design for a holder for cans, as shown.

ORLEY R. FROST.
